(57) CLAIM

I claim the ornamental design for a garment, as shown and described.

DESCRIPTION

FIG. 1 is a rear perspective view of a garment, showing my new design;

FIG. 2 is a left side view thereof;

FIG. 3 is a right side view thereof; and,

FIG. 4 is a rear view thereof.

The dot-dash broken line defines a boundary line to the claim and forms no part of the claimed design. The even length broken lines depict portions of the garment that form no part of the claimed design.
